UNITED STATES PATENT OFFICE.

WILLIAM R. WAUGH, OF HAMILTON, ONTARIO, CANADA, ASSIGNOR TO APPLEFORD COUNTER CHECK BOOK COMPANY, LIMITED, OF HAMILTON, ONTARIO, CANADA.

BOTTLE CAP.

Application filed October 2, 1926. Serial No. 139,100.

This invention relates to bottle caps such as employed to seal milk bottles and which usually comprise a simple cardboard disk adapted to be pressed within the rim of the mouth of the bottle into contact with an annular seal. The removal of these caps, without using a special tool, is troublesome and numerous caps have been brought out including a tongue or tab, usually integral with the cap, which may be bent up to serve as a finger grip whereby the cap may be removed and replaced with ease and as often as may be necessary. The difficulty in providing caps with such tongues is that, to meet the requirements of the capping machines, the surfaces of the cap must be substantially flush and it has so far been necessary to deform the cap in some way in the process of manufacture to give access for a finger nail to the end of the tab and without causing material projections above the surfaces of the cap.

It is undesirable to deform the cap in the process of manufacture as it causes extra expense and trouble in manufacture and any departure from a flat flush surface either at the upper or underside may give trouble in the capping machines or provide recesses in which dust or liquid may collect.

My object, therefore, is to devise a cap, provided with a tab, which presents substantially unbroken surfaces but in which a simple operation, when the cap is to be removed, gives access to the end of the tab.

I attain my object by defining in the cap a part to form a tab and a part adapted to be depressed by the finger or a tool to give access to the end of the tab which is adapted to be bent up to form a finger grip integrally attached at its base to the cap.

The invention is hereinafter more specifically described and is illustrated in the accompanying drawings in which

Fig. 1 is a plan view of a bottle cap constructed in accordance with my invention;

Fig. 2 a similar view showing a modification of the same;

Fig. 3 a similar view of the reverse side of the cap illustrated in Fig. 2;

Figs. 4, 5 and 6 plan views of various other modifications;

Fig. 7 a section on the lines 7—7 or 7a—7a in Fig. 1;

Fig. 8 a section on the line 8—8 in Fig. 2;

Fig. 9 a section on the line 9—9 in Fig. 2; 55
Fig. 10 a section on the line 10—10 in Fig. 2;

Fig. 11 a section on the line 11—11 in Fig. 4;

Fig. 12 a section on the line 12—12 in 60 Fig. 4;

Fig. 13 a cross section of another modification;

Fig. 14 a plan view of a preferred form;

Fig. 15 a similar view of the reverse side 65 of the cap shown in Fig. 14;

Fig. 16 a cross section on the line 16—16 in Fig. 14; and

Fig. 17 a cross section on the line 17—17 70 in Fig. 14.

In the drawings like numerals of reference indicate corresponding parts in the different figures.

Referring particularly to Figs. 1 and 2, 75 1 is a cardboard disk of ordinary material and standard size. In it are formed three cuts 2, 3 and 4, in the form of a letter H. These cuts extend entirely through the card so as to form two tongues 5 and 6. The cuts are formed with a die having thin cutting edges so that the cuts tend to close after their formation, the sealing of the cuts being completed when the cap is waxed. It is, however, possible by the use of the finger 80 or tool to depress one tongue, for instance, the tongue 6, and to thus gain access to the end of the tongue 5, which may then be raised to form a tab integrally connected at its base with the cap.

It is preferable, however, not to completely sever the sides and ends of the tongues from the cap, while it is still possible to readily depress one tongue and pull up the other. A construction for this purpose is 85 illustrated in Figs. 2, 8, 9 and 10. The tongue 5 is outlined by the lines 8—8, which extend part way through the cap from one side and the lines 9—9 which extend part way through the cap from the other side. The tongue 5 is similarly outlined by similar cuts in reverse relationship. The cuts on one side of the cap are in offset relationship to the cuts at the other side. The result is that when the tongue 6 is depressed 90 the material of the cap splits in the central plane between the cuts at the side and end of the tongue so that the sides and ends of the tongue are detached and pushed down- 100 105

wards. This exposes the end of the tab 5, which is then easily raised, the material of the cap splitting in a similar manner.

It will be noted that the ends of the 5 tongues are connected with one another by smaller uncut portions at the corners, but these readily break away when the tongues are depressed and elevated as described.

From the construction described it will be 10 seen that I have provided in the cap two areas of its surface partly outlined by lines of weakness which form tongues one of which is more readily depressed than lifted and the other more readily lifted than depressed, whereby one may be broken down 15 to give access to the end of the other, which may then be lifted to form a tab.

In Figs. 4, 11 and 12, I show a modification in which the lines 10 outline the tongue 6 and extend nearly but not quite through the cap, while the lines 11 outlining the sides of the tongue 5 extend nearly but not quite through the cap from the other side. The tongue 6 is readily depressed, the tongue 25 tearing away from the material of the cap at the under side. The tongue 5 may be lifted, the sides tearing away from the upper side of the cap. It is not possible, however, with this construction to make clean breaks, and 30 to assist the material to break cleanly I may form score marks 12 at the opposite sides of the cap as indicated in Fig. 13, these score marks being made by pressure and not by cutting.

35. In every case there has been formed areas in the cap, one of which is more readily depressed than raised and the other more readily raised than depressed.

In Figs. 1, 2, 3 and 4 the tongues are 40 shown diametrically opposed with their ends in juxtaposition. In Fig. 5 I show a modification of the tongue 5. In this case the ends of the tongue are both connected with the disk, but the tongue may nevertheless 45 be readily sprung downwardly sufficient to give access to the end of the tongue 5.

In Fig. 5 I show a modification in which the tongue 6 extends in a direction at right angles to the tongue 5.

50. In Fig. 6 I show a modification in which the tongue 6 extends in a direction at right angles to the tongue 5. Its mode of operation will, however, be substantially the same.

In Figs. 14 to 17 I show a preferred form. 55 The tongue 5 is outlined by the U-shaped cut 13 at one side of the cap and the cut 14 at the other, the cuts being offset from one another and each extending part way through the cap. The tongue 6 is formed by 60 a plurality of cuts 15 extending from the bottom of the U-shaped cut 14 parallel to its sides. These cuts preferably extend only part way through the cap. The tongue 6 being thus divided the center thereof is easily 65 pressed down from the uncut side of the tab

and access thus obtained to the end of the tongue 5.

It should be noted that the caps are shown on an enlarged scale and that the thickness 70 has been exaggerated for the sake of clearness.

What I claim is:

1. A bottle cap formed of an integral ply of cardboard having a tab formed therein with its base integrally connected with the cap, said tab being adapted to be readily pulled up to form a finger grip, said cap having a part adjacent the other end of the tab partly separated from the cap but connected therewith along a line remote from the base of the tab and adapted to be readily depressed to give access to the end of the tab remote from the base. 75

2. A bottle cap formed of an integral ply of cardboard having two areas of its surface partly outlined by lines of weakness to form adjacent parts integrally connected with the cap along separate lines remote from one another but displaceable relative to the cap, the said lines of weakness being so formed that one part is more readily depressed than lifted and the other readily depressed, whereby one may be broken down to give access to the end of the other which may then be lifted to form a tab. 85

3. A bottle cap constructed as set forth in claim 2 in which the lines of weakness are formed by cuts extending partly through the cap from one side in the case of one of said parts and from the other side in the 100 case of the other part.

4. A bottle cap constructed as set forth in claim 2 in which the lines of weakness are formed by cuts extending partly through the cap from one side in the case of one of said parts and from the other side in the case of the other part, and also, in the case of the liftable tab, by cuts offset from the cuts aforesaid positioned to facilitate the 105 lifting of the tab. 110

5. A bottle cap formed of an integral ply of cardboard having two tongues formed therein with their bases integrally connected with the cap and their opposite ends co-terminous, the said tongues being outlined by lines of weakness, the said lines of weakness being so formed that one part is readily depressed and the other more readily lifted than depressed, whereby one may be broken down to give access to the end of the other which may then be lifted to form a tab. 115

6. A bottle cap formed of an integral ply of cardboard having two diametrically opposed tongues formed therein with their bases integrally connected with the cap and their opposite ends co-terminous, the said tongues being outlined by lines of weakness, the said lines of weakness being so formed that one part is readily depressed and the other more readily lifted than depressed, 125 130

whereby one may be broken down to give access to the end of the other which may then be lifted to form a tab.

7. A bottle cap constructed as set forth in claim 5 in which the lines of weakness are formed by cuts extending partly through the cap from one side in the case of one of said parts and from the other side in the case of the other part.

10 8. A bottle cap constructed as set forth in claim 5 in which the lines of weakness are formed by cuts extending partly through the cap from one side in the case of one of said parts and from the other side in the case of 15 the other part, and, also, in the case of the liftable tab, by cuts offset from the cuts aforesaid positioned to facilitate the lifting of the tab.

9. A bottle cap formed of an integral ply 20 of cardboard having diametrically opposed tongues formed therein with their bases integrally connected with the cap and their opposite ends co-terminous, the said tongues being outlined by lines of weakness, the said 25 lines of weakness being so formed that one part is readily depressed and the other more readily lifted than depressed, whereby one may be broken down to give access to the end of the other which may then be lifted to 30 form a tab, the tongue adapted to be broken down having one or more lines of weakness formed therein parallel to its sides.

10. A bottle cap formed of an integral ply

of cardboard having diametrically opposed tongues formed therein with their bases integrally connected with the cap and their opposite ends co-terminous, the said tongues being outlined by lines of weakness, the said lines of weakness being so formed that one part is readily depressed and the other more 40 readily lifted than depressed, whereby one may be broken down to give access to the end of the other which may then be lifted to form a tab, the tongue adapted to form the tab having its lines of weakness formed by 45 cuts offset at opposite sides of the cap, the tongue adapted to be broken down having one or more lines of weakness formed therein parallel to its sides.

11. A bottle cap formed of an integral ply 50 of cardboard having diametrically opposed tongues formed therein with their bases integrally connected with the cap and their opposite ends co-terminous, the said tongues being outlined by lines of weakness, the said 55 lines of weakness being so formed that one part is readily depressed and the other more readily lifted than depressed, whereby one may be broken down to give access to the end of the other which may then be lifted to 60 form a tab, the tongue adapted to form the tab having its lines of weakness formed by cuts offset at opposite sides of the cap.

Signed at Hamilton, Ont., this 23rd day of August, 1926.

WILLIAM R. WAUGH.
